Primary Examiner — Mimosa De(74) *Attorney, Agent, or Firm* — Price Heneveld LLP(57) **CLAIM**

The ornamental design for seating arrangement, as shown.

DESCRIPTION

FIG. 1 is a perspective view of a seating arrangement embodying the present invention;

FIG. 2 is a front elevational view of the seating arrangement; FIG. 3 is a first side elevational view of the seating arrangement;

FIG. 4 is a rear elevational view of the seating arrangement; FIG. 5 is a second side elevational view of the seating arrangement; FIG. 6 is a top plan view of the seating arrangement; and, FIG. 7 is a bottom plan view of the seating arrangement.
